UNITED STATES PATENT OFFICE.

GREENLEAF WHITTIER PICKARD, OF NEWTON, MASSACHUSETTS, ASSIGNOR TO
WIRELESS SPECIALTY APPARATUS COMPANY, OF BOSTON, MASSACHUSETTS, A
CORPORATION OF NEW YORK.

TESTING APPARATUS.

Application filed April 23, 1920. Serial No. 376,132.

To all whom it may concern:

Be it known that I, GREENLEAF W. PICKARD, a citizen of the United States, residing at Newton, in the county of Middlesex and 5 State of Massachusetts, have invented certain Improvements in Testing Apparatus, of which the following description, in connection with the accompanying drawings, is a specification, like reference characters 10 on the drawings indicating like parts in the several figures.

This invention relates to distinguishing bad from good sheets of mica or other dielectric or insulating materials. The invention 15 will be herein disclosed as embodied in apparatus designed particularly for testing dielectric elements to be used in electrical condensers. These elements are subjected to the distinguishing operation before being 20 assembled in the condenser so that the defective elements can be eliminated. It can thus be definitely determined before the assembling operation is begun that only perfect dielectric elements shall go into the construction of the condenser, and the expense 25 and annoyance which otherwise would be caused by the presence of defective elements thus is eliminated.

The present invention has for its chief object to devise an apparatus with which such distinguishing method can be performed very accurately and rapidly and which will require a minimum of skill and care on the part of the operator. It is a further important object of this invention to devise 30 an apparatus of this character which, in addition to performing and testing operation, will also automatically separate the dielectric electrically distinguishing operation, 35 also will separate the defective dielectric sheets or films from the good ones by means controlled by the presence of defects in the bad sheets.

The nature of the invention will be readily understood from the following description and the novel features will be particularly pointed out in the appended claims.

Referring now to the accompanying drawings, 40 Figure 1 is a diagrammatic view of an apparatus embodying the present invention;

Fig. 2 is a front elevation of a portion of the apparatus; and

Fig. 3 is a plan view of a sheet of mica to 55 be tested.

Preliminary to a detailed description of the apparatus it should be stated that the entire surface of a mica sheet, or other dielectric element of a condenser, is not subjected to a dielectric strain while in use. That is, the conducting elements are smaller than the dielectric elements so that a margin is left around the entire edge of each dielectric element which is substantially free from 60 the dielectric strain, this margin serving primarily to prevent the current from jumping around the edge of the mica sheet between the two adjacent conducting elements 65 separated by said sheet.

In Fig. 3 M indicates a mica sheet and m the active area of the sheet; that is, the area subjected to the dielectric strain. It is this area m which must be tested but it is not necessary to test the dielectric strength of 70 the inactive margin, and in the present machine it is contemplated that this margin will not be tested.

The apparatus shown comprises two metal rolls 2 and 3, respectively, mounted one 75 above the other, and rotating on metal shafts which are supported in frame pieces 4-4 made of insulating material. Thus the rolls are electrically insulated from each 80 other at all places except at their peripheries. The rolls may be driven from any suitable source of motive power and they are connected together by gears 5 and 6 made of insulating material such as bakelite, fibre, 85 or the like. They are rotated in the directions indicated by the arrows in Fig. 1 and the mica sheets are fed between the rolls 90 one at a time.

Each roll is of a length equal to one dimension of the area m so that when the 95 sheets are run through them the opposite margins of each sheet project beyond the ends of the rolls so that there will not be such a discharge from one roll to the other over the edges of the sheet tested as to prevent the proper testing of the sheet.

These two rolls are connected in a high potential circuit comprising the secondary 7 of an induction coil or transformer, one terminal of this secondary being connected 100 by a conductor 8 to the roll 2 while the other terminal is connected by a conductor 9 through the primary 10 of another induc-

tion coil to the lower roll 3. For convenience in making these connections, the ends of the shafts on which the rolls are mounted are extended through one of the supports 4, 5 as indicated at the left of Fig. 2, and spring terminals 11 and 12 bear against these projecting ends, the conductors 8 and 9, respectively, being connected to these terminals.

The primary circuit includes a battery 14, 10 a primary coil 15, a vibrator 16, and two switches designated at 17 and 18, respectively. The switch 17 comprises a pivoted conducting arm 19 carrying a roll 20 at its upper end and normally held by a spring 21 15 against the end of a stop screw 22 and a spring mounted contact 17^a with which arm 19 engages to close the circuit. The other switch 18 is like the switch 17 and includes a pivoted conducting arm 23 carrying a roll 24 at its upper end and normally held open by a spring 21^a. This primary circuit, therefore, is normally open. It will be seen from an inspection of Fig. 2 that the rolls 20 and 24 are mounted closely adjacent to 20 the opposite ends of the rolls 2 and 3 and that the upper edges of the rolls 20 and 24 lie just above the level of the line of contact of the rolls 2 and 3. The distance from the line of contact of the rolls 2 and 3 with 25 the mica sheet to the top of each roll 20 and 24 is equal to the width of the inactive margin of the mica sheets shown at m' , Fig. 3.

Normally both the primary and secondary circuits are inactive since the switches 17 30 and 18 are open. When, however, a sheet of mica is fed between the rolls 2 and 3, the forward or leading edge of the mica sheet first engages the roll 20 and depresses it, thus closing the switch 17. When this edge 35 of the sheet emerges from between the rolls a distance equal to the width of the margin m' , Fig. 3, the roll 24 will then be moved far enough by its engagement with said sheet to close the switch 18. At this instant, therefore, the primary circuit is closed 40 and the interrupted current flowing there-through creates a high potential in the secondary circuit which potential is impressed across the sheet of mica between the rolls. 45 That is, the rolls form, in effect, terminals for the high potential circuit. As the sheet is advanced by the rolls, all parts of its active area m are subjected to the potential created in the secondary circuit. But as 50 soon as the rear or trailing edge of the sheet leaves the roll 20, the spring 21 opens the switch 17 and thus interrupts the action of the primary, and consequently, also, the secondary circuit. The switch 18 is opened an 55 instant later by its spring when the mica moves out of contact with it. It will be understood, of course, that the springs that operate the arms 19 and 23 are very light.

If the mica has no fault or flaw which 60 will permit the applied potential to drive a

current through the flaw, no current will flow in the secondary circuit. If, however, the sheet has a hole in it, or for any other reason breaks down at a fault or flaw, then a current will flow through the secondary 70 circuit. This current energizes the primary coil 10 which induces a current in the secondary 27 of a low potential circuit that also includes a relay coil 28. The energizing of this coil lifts an armature 29 thus 75 closing a switch 30 and causing a flow of current from a battery 31 through a solenoid 32. This solenoid attracts an armature 33 on the depending end of a plate 34 which is pivoted at 35 and normally rests against 80 a stop screw 36.

It will be seen that the plate 34 forms normally a continuation of an inclined apron or chute 37 down which the mica sheets slide as they are ejected from between the rolls 2 and 3. If the plate 34 is in its normal position, these mica sheets will slide into the forward part of a receptacle 38, but if the plate 34 is tipped into its dotted line position as shown in Fig. 1, the mica sheet 85 then will drop into the rearward part of this receptacle. A partition, not shown, separates the front and rear portions of the receptacle. It will thus be seen that the plate 34 is operated automatically to separate the perfect from the imperfect sheets of mica, the perfect sheets sliding into the forward part of the receptacle 38 and the defective sheets into the rearward part. That is, the plate 34 acts as an automatic switch or deflector to direct the perfect and imperfect sheets into different paths.

In case a sheet of mica under test contains a small hole or other flaw near its forward edge while the remainder of the sheet is perfect, there is danger that the switch or deflector plate 34 after being swung into its dotted line position will drop back again before the imperfect sheet is delivered due to the fact that the flow of current through the secondary circuit will be cut off at a relatively early point in the testing of that sheet. In such an event the defective sheet of mica would be delivered to the forward part of the receptacle 38 with the perfect sheets. In order to prevent this action the core of coil 28 that operates the armature 29 is provided with a locking winding 40 which is in circuit with a switch 41 that is closed when the relay 28 is energized and is also in circuit with a battery 42 and another switch comprising the pivoted arm 19 and the stop screw 22. The latter switch is in parallel with a switch 43 in circuit with winding 40 and normally held open by a spring 44 but arranged to be closed by a solenoid 45 in series with the switches 17 and 18 and with the battery 14.

This parallel arrangement of switches ensures that after the switch arm 29 has once

been lifted it will be held in its raised position due to the action of the locking winding 40 as long as either switch 43 or switch 19, 22, is closed, the two switches operating 5 alternately. That is, if the coil 28 has been energized to raise armature 29, so long as the mica film is under test and the windings 7 and 15 are energized, the armature 29 will be locked in its "up" position, the switch 10 43 being then closed. As soon, however, as the rear end of the mica film leaves the roll 20 the primary circuit will be broken by the opening of the switch 17. This will deenergize the relay 45 opening switch 43 15 but it will not open the locking circuit because the parts 19 and 22 will, by that time, have come into engagement and will still keep this circuit closed. When, however, a new mica film is fed into the machine 20 the depression of the roll 20 will break the contact between the parts 19 and 22 and the locking circuit then will be opened, allowing the armature 29 to drop into its lower position, thus opening the switches 30 and 25 41 and releasing the deflector plate 34 which will fall back against its stop 36.

To prevent the opening of the locking circuit upon the breaking of the circuit of coil 45 and the opening of switch 43, a leaf 30 spring 46 is attached at one end to member 19 and is free at its opposite end to yieldingly engage and disengage contact 22. When roll 20 is depressed, member 19 moves downwardly and engages contact 17^a and 35 slightly depresses it by reason of its spring mounting. By this time, spring 46 has disengaged contact 22. When roll 20 is released, member 19 raises, the contact 17^a following in engagement therewith until spring 40 46 again engages contact 22. Thereafter member 19 and contact 17^a separate by reason of the continued movement of member 19, this continued movement being allowed by spring 46. The switches 17 and 18 are 45 so arranged that the potential is applied while the sheet is held between the rolls and the potential is released before the sheet is released, thus preventing discharges between the terminals which tend to heat the 50 mica, causing it to deteriorate. It is to be understood that other apparatus for performing this method of applying and releasing potential only while the sheet is pressed between terminals may be used.

55 It will now be evident that this invention provides a very simple apparatus with the aid of which mica sheets or films can be tested very rapidly; and that the machine, in addition to testing the sheets, will automatically separate the sheets that are defective from the good sheets. The voltage impressed across the rolls 2 and 3 can be adjusted as desired by using a suitable type of transformer or induction coil, so that the 60 same apparatus at different times can be

used for different lots of micas of different thicknesses.

While I have herein shown and described the best embodiment of the invention of which I am at present aware, it will readily 70 be appreciated that this embodiment may be modified in many particulars without departing from the spirit or scope of this invention.

While the dielectric material to be tested has been referred to above and also in the appended claims as "mica", it will be understood that other dielectrics are the equivalent of mica so far as the present invention is concerned. 75

80 What is claimed as new is:

1. An automatic mica-sheet flaw-detecting and selecting machine, which comprises two electrically conducting members constituting circuit terminals having sufficiently wide continuous conducting surface areas to engage continuously substantial widths of the opposite surfaces of an intervening mica sheet; means causing an electric current to flow through a flaw in a defective intervening mica which does not cause a current to flow through a good intervening mica; mechanism moving successive micas to positions between and ejecting them from between said conducting members; and 90 mechanism controlled by such current flow through defective micas and segregating the good and the bad ejected micas. 95

2. An automatic mica-sheet flaw-detecting machine comprising, in combination, a pair of electrically conducting rolls mounted to be adjacent to one another for simultaneously engaging opposite portions of the two surfaces of a mica sheet, means for driving said rolls to cause them to feed said sheet therethrough, and a high potential circuit in which said rolls are connected and for which they form terminals, whereby a flow of current in said circuit is normally prevented by the presence of good portions of said mica sheet between the rolls but is permitted when a defective part of the sheet passes between said rolls. 100

105 3. An automatic mica-sheet flaw-detecting machine comprising in combination a pair of electrically conducting rolls mounted to be adjacent to one another for simultaneously engaging opposite portions of the two surfaces of a mica sheet, means for driving said rolls to cause them to feed said sheet therethrough, and a high potential circuit in which said rolls are connected and for which they form terminals, and controlling means for said circuit arranged to be operated by the forward edge of the mica sheet as the rolls draw the sheet between them. 110

115 4. An automatic mica-sheet flaw-detecting and selecting machine, which comprises two electrically conducting members constitut- 120

125

130

- ing circuit terminals and having sufficiently wide continuous conducting surface areas to engage continuously substantial widths of the intervening mica sheet under test;
- 5 means causing an electric current to flow through a flaw in a defective intervening mica which does not cause a current to flow through a good intervening mica; mechanism moving successive micas to position
- 10 between and ejecting them from between said conducting members; controlling means for said current-causing means and itself controlled by said moving mechanism; and mechanism controlled by the current
- 15 flow through defective micas and segregating the good from the bad ejected micas.
5. An automatic mica-sheet flaw-detecting and selecting machine, which comprises two electrically conducting members constitut-
- 20 ing circuit terminals having sufficiently wide continuous conducting surface areas to engage continuously substantial widths of the opposite surfaces of an intervening mica sheet; means causing an electric current to
- 25 flow through a flaw in a defective intervening mica which does not cause a current to flow through a good intervening mica; mechanism for moving successive micas to positions between and ejecting them from be-
- 30 tween said conducting members; at least one of said terminals having a width less than the mica sheet whereby the sheet in testing position extends to a limited degree beyond said terminal; controlling means for said
- 35 current-causing means and itself controlled by said moving mechanism; and mechanism controlled by said current flowing through defective micas and segregating the good from the bad ejected micas.
- 40 6. A mica testing machine comprising, in combination, a pair of rolls for simultaneously engaging opposite faces of a mica sheet, means for driving said rolls to cause them to feed said sheet therethrough, and a
- 45 high potential circuit in which said rolls are connected and for which they form terminals, a device movable into either one of two operative positions for controlling the path taken by the ejected mica sheets, and
- 50 automatic means for shifting said device from one of said positions to the other to direct the perfect and imperfect sheets into different paths upon their discharge from between said rolls and for automatically holding said device in its shifted position until after the sheet for which it is shifted has passed said device.
- 55 7. An automatic mica-sheet flaw-detecting machine comprising, in combination, a pair of electrically conducting rolls mounted to be adjacent to one another for simultaneously engaging opposite portions of the two surfaces of a mica sheet, means for driving said rolls to cause them to feed said sheet therethrough, means for impressing a high

potential across said rolls whereby a mica sheet fed between them will be subjected to a dielectric strain, a deflector normally held in position to direct the sheets ejected from between said rolls in a predetermined path, and means acting automatically upon the passage between the rolls of a dielectrically weak portion of the mica sheet, to shift said deflector into a position causing the defective sheet to follow a different path.

8. A mica testing machine comprising, in combination, a pair of rolls for simultaneously engaging opposite faces of a mica sheet, means for driving said rolls to cause them to feed said sheet therethrough, and a high potential circuit in which said rolls are connected and for which they form terminals, whereby a flow of current in said circuit is normally prevented by the presence of said mica sheet between the rolls but is permitted when a defective part of the sheet passes between said rolls, a deflector normally held in a position to direct the sheets ejected from between said rolls in a predetermined path, electro-magnetic means operative automatically upon a flow of current through said circuit permitted by the passage of a defective sheet to shift said deflector into a position causing the ejected sheet to follow a different path, and means operative to ensure the retention of said deflector in its shifted position until said defective sheet has been directed into the desired path.

9. An automatically operating mica-sheet flaw-detecting and selecting machine comprising, in combination, a pair of electrically conducting rolls mounted to be adjacent to one another for simultaneously engaging opposite portions of the surfaces of a mica sheet, means for driving said rolls to cause them to feed said sheet therethrough, and a high potential circuit in which said rolls are connected and for which they form terminals, whereby a flow of current in said circuit is normally prevented by the presence of said mica sheet between the rolls but is permitted when a defective part of the sheet passes between said rolls, a deflector normally held in a position to direct the sheets ejected from between said rolls in a predetermined path, electro-magnetic means for shifting said deflector into a different position, and a relay controlling the operation of said electro-magnetic means and arranged to be energized by a flow of current through said high potential circuit.

10. A mica testing machine comprising, in combination, a pair of rolls for simultaneously engaging opposite faces of a mica sheet, means for driving said rolls to cause them to feed said sheet therethrough, and a high potential circuit in which said rolls are connected and for which they form terminals, whereby a flow of current in said cir-

cuit is normally prevented by the presence of said mica sheet between the rolls but is permitted when a defective part of the sheet passes between said rolls, a deflector normally held in a position to direct the sheets ejected from between said rolls in a predetermined path, electro-magnetic means for shifting said deflector into a different position, a relay controlling the operation of 5 said electro-magnetic means and arranged to be energized by a flow of current through said high potential circuit, and a locking circuit for maintaining said electro-magnetic means energized after its operation has been 10 initiated until after the testing operation on the sheet which permitted the flow of current through said circuit has been completed.

11. A mica testing machine comprising, in combination, a pair of rolls for simultaneously engaging opposite faces of a mica sheet, means for driving said rolls to cause them to feed said sheet therethrough, a high potential circuit in which said rolls are connected and for which they form terminals, 15 whereby a flow of current in said circuit is normally prevented by the presence of said mica sheet between the rolls but is permitted when a defective part of the sheet passes between said rolls, a deflector normally held in a position to direct the sheets ejected from between said rolls in a predetermined path, electro-magnetic means operative automatically upon a flow of current through said circuit permitted by the passage 20 of a defective sheet to shift said deflector into a position causing the ejected sheet to follow a different path, and a locking circuit for said electro-magnetic means operative to ensure the retention of said deflector in its shifted position until said defective sheet has been directed into the desired path, said locking circuit including a switch arranged to be operated by the presentation of the next sheet of mica to said 25 rolls to open said locking circuit and thereby enable said deflector to return to its original position.

12. An automatically operating mica-sheet flaw-detecting and selecting machine, 30 which comprises a pair of electrically conducting members constituting circuit terminals having sufficiently wide continuous conducting surfaces to engage continuously substantial widths of the opposite surfaces of the mica-sheet; means causing an electric current to flow through a flaw in a defective mica between said conducting members which does not cause a current to flow 35 through a good mica so located; means for ejecting the micas successively from between said conducting members; and mechanism controlled by said current flow through defective micas and segregating the good and the bad ejected micas.

13. A testing apparatus comprising, in

combination, two electrically conducting members mounted to engage simultaneously opposite faces of a sheet of mica, a high potential circuit connected to said members and for which the members form terminals, a primary circuit supplying power to said high potential circuit, and controlling means for said primary circuit normally holding the latter circuit open but mounted and arranged to be operated to close said circuit upon the presentation of a mica sheet in testing position.

14. A mica testing machine comprising, in combination, a pair of rolls for simultaneously engaging opposite faces of a mica sheet, means for driving said rolls to cause them to feed said sheet therethrough, and a high potential circuit in which said rolls are connected and for which they form terminals, switch operating elements controlling said circuit and maintaining it normally inactive but mounted and arranged to be engaged by both the leading and trailing edges of said mica sheet whereby said circuit is inactive whenever either one of said elements is not engaged by a mica sheet.

15. A mica testing machine comprising, in combination, a pair of rolls for simultaneously engaging opposite faces of a mica sheet, means for driving said rolls to cause them to feed said sheet therethrough, a high potential circuit in which said rolls are connected and for which they form terminals, and two normally open switches connected 95 in series and controlling said circuit, said switches having operating elements mounted, respectively, one in front of and the other behind the line of contact of said rolls with the mica sheet whereby both of said elements are engaged by the sheet as it is fed through the rolls.

16. A mica testing machine comprising, in combination, a pair of rolls for simultaneously engaging opposite faces of a mica sheet, means for driving said rolls to cause them to feed said sheet therethrough, a high potential circuit in which said rolls are mounted and for which they form terminals, a primary circuit supplying power to said high potential circuit, and two switches connected in said primary circuit in series with each other, means for normally holding said switches open, an operating element for each of said switches, said elements being located one in front of and the other behind the line of contact of said rolls with the mica sheet whereby they are operated to close the switches by their contact with said sheet.

17. The method of applying a flaw-detecting difference of electrical potential to the opposite surfaces of a dielectric sheet between two circuit terminals having wide continuous conducting surfaces continuously 120 engaging substantial widths of the opposite

- surfaces of the sheet, which consists, after locating the sheet between the terminals, in successively pressing the terminals into firm engagement with the sheet and relieving the sheet from such terminal-compression, causing such pressing and release of the sheet to effect the application and the discontinuance respectively of the flaw-detecting potential to the terminals.
- 10 18. Apparatus for distinguishing good mica sheets from similar sheets possessing minute defects not readily observable, comprising a pair of electrically conducting members having sufficiently wide continuous surfaces to engage continuously substantial widths of opposite mica faces; mechanism moving successive micas to positions between said conducting members; and means controlled by said moving mechanism and operating while a mica is between said conducting members, and causing the application of such a potential difference to said conducting members as will cause a current to flow through a defect in a defective mica but not through a good mica.
- 15 19. An automatically operating machine for detecting flaws in dielectric sheets which comprises a pair of electrically conducting members constituting circuit terminals having sufficiently wide continuous conducting surface areas to engage continuously substantial widths of the sheet; means for moving the sheets to positions between and ejecting them from between said terminals; means controlled by the sheet in its movement and connecting the terminals in their circuit; means associated with said circuit for causing the application of such potential difference to said terminals as will cause a current to flow through a defect in a defective mica but not through a good mica; and means automatically returning said connecting means to its normal disconnecting position upon further movement of said sheet but prior to the ejection thereof.
- 20 20. An automatically operating mica-sheet flaw-detecting machine, which comprises a pair of sheet-feeding rolls mounted to be normally in peripheral contact with one another; means for rotating the rolls to feed the mica sheet between them; and means for subjecting the mica sheet to a high electric stress while it is being fed by said rolls.
- 25 21. An automatically operating mica-sheet flaw-detecting machine, which comprises a pair of sheet-feeding rolls mounted to be normally in peripheral contact with one another; means for rotating the rolls to feed the mica sheet between them; insulating supports for the ends of said rolls and between which the sheet passes while being fed between the rolls; and means for subjecting the mica sheet to a high electric stress while it is being fed by said rolls.
22. An automatically operating machine for detecting flaws in a mica sheet, which comprises two conducting members constituting circuit terminals having sufficiently wide and continuous conducting surfaces to engage continuously a substantial portion of the width of the sheet; and means, operated by movement of said sheet and only when the sheet is in such engagement with both terminals, to apply and remove, successively, a difference of electrical potential between said terminals and the opposite surfaces of the sheet.
- 27 23. An automatically operating mica-sheet, flaw-detecting machine, which comprises rotatable sheet-feeding means; and means, operating while the sheet is being fed by said means, causing an electric current to flow through a flaw in a defective mica sheet which does not cause a current to flow through a good mica sheet.
- 28 24. Apparatus for distinguishing and segregating good mica sheets and similar sheets possessing minute defects not otherwise observable, said apparatus comprising two electrically conducting members having sufficiently wide continuous surfaces to engage continuously substantial widths of opposite mica faces; mechanism moving successive micas to positions between and ejecting them from between said conducting members; means controlled by said moving means and operated when a mica is engaged by and between said conducting members and applying such a potential difference to said conducting members as will cause a current to flow through a defective mica but not through a good mica; and mechanism controlled by such current flow through defective micas and segregating the good and the bad ejected micas.
- 29 25. Apparatus for distinguishing good mica sheets from similar micas possessing minute defects not readily observable, said apparatus comprising two members having relatively movable electrically conducting mica-engaging surfaces; mechanism moving a mica-engaging surface of at least one of said conducting members toward the other into position to engage a mica between them; means applying to said conducting surfaces such an electrical potential difference as to cause a flow of current through a defect in a defective mica but not through a good mica; a switch controlling said potential applying means; and mechanism controlled by continued operation of said conducting member moving means while the mica is engaged by said conducting surfaces, and operating said switch to cause operation of said means for applying potential difference.
- 30 In testimony whereof I have signed my name to this specification.
